(57) **CLAIM**

We claim the ornamental design for a clip for a writing instrument, as shown and described.

DESCRIPTION

FIG. 1 is a perspective view of a clip for a writing instrument showing our new design;

FIG. 2 is a front elevational view thereof;

FIG. 3 is a rear elevational view thereof;

FIG. 4 is a right side elevational view;

FIG. 5 is a left side elevational view;

FIG. 6 is a top plan view thereof;

FIG. 7 is a bottom plan view thereof; and,

FIG. 8 is a second perspective view thereof, the writing instrument depicted by means of broken lines being shown for illustrative purposes only and forming no part of the claimed design.

The portion of the clip depicted by means of broken lines in FIGS. 3 through 7 has been shown for illustrative purposes only and forms no part of the claimed design.
